UNITED STATES PATENT OFFICE.

DAVID JAMES HURLEY, OF SALE, VICTORIA, AUSTRALIA.

CONTROLLER FOR DOORS AND LIKE MOVABLE STRUCTURES.

1,113,997.

Specification of Letters Patent.

Patented Oct. 20, 1914.

Application filed June 17, 1913. Serial No. 774,181.

To all whom it may concern:

Be it known that I, DAVID JAMES HURLEY, a subject of the King of Great Britain, residing at Sale, in the State of Victoria, 5 Commonwealth of Australia, piano tuner, have invented certain new and useful Improvements in Controllers for Doors and Like Movable Structures, of which the following is a specification.

10 This invention relates to improvements in controllers for doors and like movable structures and has been devised in order to provide exceedingly efficient apparatus which by suitable adjustment of its parts 15 can be made to retain a door or the like in a desired position for ventilation or other purposes and also for insuring the door closing automatically when desired without banging or occasioning noise. For brevity, 20 hereinafter the term door will be held to include windows, gates, and like movable structures which hinge or pivot vertically.

My invention broadly consists of a screw plate or the like for attachment to a door 25 frame or other fixture and having means for detachably and pivotally affixing a curved rod thereto in such a manner that it will automatically adjust itself to the movement and position of the door. The 30 closing action is produced by arranging a spring to act on a pivoted rod or arm having its free end engaging a vertical member carried by a vertical portion mounted on a bracket and which also carries a frictional 35 gripping member slidably mounted on the curved rod. The action of the gripping member is controlled by a screw or the like and can be arranged to move freely over or to firmly grip the said rod as preferred.

40 In order that the details of construction and action of my invention may be more readily understood reference will now be made to the accompanying sheet of explanatory drawings, wherein—

45 Figure 1 is a view in plan of the invention. Fig. 2 is a view in side elevation of part of the device shown in Fig. 1. Fig. 3 is a view in elevation, partly in section, of portion of Fig. 2, while Figs. 4 and 5 are 50 views in side and front elevation, respectively, of a bracket forming part of the invention. Fig. 6 illustrates in perspective a further modification of the invention.

The numeral 1 designates a screw plate 55 having two bosses 2 formed thereon or fitted thereto in an approved way. This plate 1

is secured to the frame of the door at that part which is over the pivot or hinge point thereof. The bosses 2 on the said screw plate 1 provide pivotal supports for the inwardly turned ends of a curved rod 3 and the ends of said rod are prevented from becoming disengaged from said bosses by one or more pins 4. The curvature of the said rod 3 is perfectly regular and forms an arc having its center in the vertical line or axis on which the door is hinged or pivoted.

If preferred, the screw plate 1 can be made in two parts, each part being arranged to carry a boss 2 lug or socket for pivotally 60 supporting the ends of the rod 3 so that it will rise and fall to accommodate itself to the movement and position of the door.

The curved rod 3 is adapted to pass through a casing 36 fitted to the projecting 65 arm 7 of a bracket 8 affixed to the door in an approved way. The said casing 36 surrounds the curved rod 3 and is preferably lined with rubberized leather 9 or other similar material which is adapted to be 70 pressed upon the periphery of the rod 3 by the action of a screw 10 of preferred construction. A curved plate 17 is positioned between the end of the screw 10 and the lining 9 to insure the whole surface of the said 75 lining being forced upon and so provide a good frictional grip of the rod 3 when it is desired to secure the door fixedly in position. The said curved plate 17 may extend almost around the lining in which case it is 80 made of metal that will permit of it springing open when the pressure of the screw 10 is removed.

If preferred, a curved plate 18 similar to 85 17 can be placed above the lining 9 which 90 can be made in two corresponding parts and conveniently secured to the curved plates.

The adjusting screw 10 can be formed with a peripheral groove which is adapted 95 to engage the point of a screw pin 20 adapted to retain it in an operative position.

A modification of the invention consists in making the curved rod 3 without the inwardly turned portions and passing their 100 ends through slots 27 in the plate 1 see Fig. 6. The said slots 27 are enlarged at one end to permit of the ends of the rods being passed freely through the plate.

110 Recesses 28 are formed in the top and bottom of the curved rod 3 and adjacent to each end thereof. The thickness of metal

left between the said recesses 28 is slightly less than the width of the narrow portions of the slots 27 in the plate 1 so that when the rods 3 are passed through the plate they 5 may be moved sidewise to be engaged by the narrow parts of the slots. This connection between the plate 1 and curved rod 3 permits the latter to have a free pivotal movement sufficient for all requirements. The 10 said slots can be arranged with their enlarged portions at the inner or outer ends thereof and the rod can be pressed inwardly or pulled outwardly to permit of the ends being passed therethrough. When the rod has been passed through the slots as above 15 described it is released and the recessed ends will spring into the narrow portions of the slots.

To insure the ends of the rods being retained in the slots, pawls 29 can be employed 20 and secured to the plate as shown in the drawings. The said pawls 29 can be fitted to either side of the plate and can be given any approved shape.

The casing 36, provided with internally 25 disposed gripping members is detachably fitted to a vertical portion 37 of the bracket 8. The means for detachably affixing the casing 36 to the bracket 8 may comprise pawls 38 and studs 39 of preferred construction. The said pawls are pivoted on screws 40 fitted to the sides of the vertical portion of the bracket 8 and the studs 39 are fitted to or 30 formed on the sides of the casing 36.

A constant closing pressure may be maintained on the door by means of a pivoted arm 41 and helical tension spring 42 of approved 35 form. A bearing is provided for the pivoted end of the arm 41 in the lug 43 or the like on the screw plate 1 and its outer and free end is adapted to bear against a jaw 44 or grooved roller 45 fitted to the vertical portion 37 of bracket 8 carried on the upper edge of the door. The jaw 44 can be 40 given any approved formation and it can be made integral with or be detachably fitted to the bracket 8. One end of the helical tension spring 42 is secured to a stud 46 or the like on that end of the screw plate 1 near 45 which the bracket lies when the door is closed and the opposite end is fitted to the pivoted arm 41 at a point near its pivot end.

From the foregoing description it will be 50 readily understood that the invention provides for a thorough and efficient regulator for doors and the like which can be operated or controlled easily by a man, woman or child.

In operation the door or other movable 55 structure fitted with the invention can be retained in any desired position and can

be moved only by a predetermined amount of force which will be governed by the frictional pressure of the gripping member.

By means of the apparatus a person can 60 fix a door or other movable structure very slightly open so that intruders may be kept out, or the door may be retained wide open, while the amount of opening and closing 65 movement can be regulated by effecting a 70 suitable adjustment of the parts, as preferred.

What I do claim is:—

1. The combination with a screw plate for 75 attachment to a door frame, of a curved rod pivotally supported on said plate over the path of the door, a bracket fitted to the door and engaging said rod, a casing surrounding said rod and detachably secured to the bracket, pieces of gripping material fit- 80 ted within said casing, curved plates and a screw in said casing designed to press said pieces upon the rod, a member fitted to said bracket and disposed to receive and have sliding engagement with the outer end of 85 an arm fitted to the screw plate, and a spring connection between said arm and plate, substantially as described.

2. The combination with a curved rod to 90 be set over the path of the door, of a bracket fitted to and loosely engaging said rod, said bracket being carried by the door, a casing detachably connected to said bracket by hook-like members, and adjustable gripping 95 devices in said casing.

3. The combination with a curved rod to 100 be set over the path of a door and having fixed pivotal supports to be secured to the door frame, of a bracket fitted to the door and a casing detachably fitted to said bracket and having internally disposed gripping members for engaging said rod, substantially as described.

4. The combination with a plate to be 105 affixed to the door frame, said plate having slots with enlarged ends, of a curved rod having recesses adjacent to its ends and adapted to engage the narrow portions of the slots in the said plate.

5. The combination with a plate to be 110 affixed to the door frame, said plate having slots adapted to receive the ends of a curved rod and support it over the path of the door, of pawls for retaining the ends of said rod in engagement with the slots.

In witness whereof I have signed this 115 specification in the presence of two witnesses.

DAVID JAMES HURLEY.
